UNITED STATES PATENT OFFICE.

CORNELL FLAGSTAD AND OSCAR A. FLAGSTAD, OF MINNEAPOLIS, MINNESOTA.

CRATE.

Application filed November 27, 1925. Serial No. 71,636.

This invention relates to improvements in crates, and the primary object is to provide a crate with means of a novel, practical and efficient nature, for suspending and securing objects, such as automobile radiators, within the crate, whereby such objects will be adequately braced against shifting movements within the crate, and whereby they will be so supported that the lowermost object will not need to bear the weight of those above it. Further and more specific objects will be disclosed in the course of the following specification, reference being had to the accompanying drawings, wherein:

Fig. 1 is a sectional plan view of the crate, as on the line 1—1 in Fig. 3.

Fig. 2 is a sectional elevation about as on the line 2—2 in Figs. 1 and 3.

Fig. 3 is a sectional elevation as on the line 3—3 in Fig. 1.

Fig. 4 is an enlarged detail perspective view of one of the supporting irons.

Fig. 5 is an enlarged end view of one of the spacing blocks, and,

Fig. 6 is a sectional view as on the line 6—6 in Fig. 5.

Referring to the drawings more particularly and by reference characters A designates the base or bottom section of a crate having side sections B and C, end sections D and E and a cover or top section F. This crate is shown as of the rigid or non-collapsible type for the purpose of simplifying and rendering more distinct the illustrations and the application of our invention, but it will be obvious that the invention is also applicable to collapsible or folding crates, and may, for instance, be readily embodied in folding crates such as shown in our co-pending applications for patents, Ser. Nos. 736,535 and 12,974, which show collapsible crates which are also primarily intended for shipping automobile radiators.

The walls or vertical sections of the present crate are preferably made up of two layers of crossed slats, i. e. horizontal and vertical slats, or boards, nailed together, and the side sections B and C are provided with pairs of directly opposed vertical channels and nailed to the side walls are arranged three pairs of opposed brackets 11—12, 13—14 and 15—16, one of which is clearly shown in Fig. 4.

Each of the members 11—16 is made up of a single piece of sheet metal having two tongues 17 and 18, the latter of which is

provided with a U-shape struck out pocket 19, arranged to fit snugly in one of the channels 7—10, while the tongue 17 extends across the channel to act as a support. 60

The crate shown is adapted to contain four radiators W, X, Y and Z, of common and well known construction, and each has the usual offset water receptacle 20, hose connection 21, laterally extending flanges 22, by which the radiator is bolted to the chassis, and a nipple 23 to which is secured a rod which braces the radiator in place on the car. 65

The first radiator, W, is placed in the crate, face down upon the base A, and although its flanges 22 extend into the channels 7 and 9, of the side sections B and C, said flanges fit snugly between blocks 22^a, on the base, so as to firmly brace the crate against shifting movement on the base. 70

The second radiator X is placed over the radiator W, but face up and in reverse position so that its flanges 22 will extend into the channels 8 and 10. The flanges also snugly engage in the pockets 19 of the brackets 11 and 12, and rest upon the upper edges of the tongues 17. 75

The third radiator Y is placed over the radiator X, but in the same corresponding position as radiator W, so that its head end will rest on the foot end of the radiator X, while the flanges 22 at its foot end engage the pockets 19 and tongue 17 of the brackets 13 and 14, so that said brackets will carry said foot end and not allow it to bear down 80 upon the head end of the radiator X. 85

The fourth radiator Z has the same relative position as radiator X and its flanges 22 are carried in the brackets 15 and 16 to suspend the foot end of that radiator. The cover F of the crate lies immediately over the face of the radiator Z so as to prevent vertical play thereof and to support the same should the filled crate be turned up side down. 95

Spacing blocks W¹, X¹, Y¹ and Z¹ are employed to space the opposite ends of the radiators W and X, and Y and Z from each other, so as to give sufficient clearance for the hose connectors 21. These blocks, all of which are similar, are provided, as shown in Figs. 5 and 6, with holes 24, to receive the nipples 23, and suitable means, such as spring actuated member 25, to frictionally engage the nipples 23, to prevent displacement of the blocks as the radiators are set into and removed from the crates. 100

It may here be noticed that the block X^1 supports the head end of the radiator X from the foot end of the radiator W , and supports W on X in case the crate is turned over. The foot end of radiator X is carried by the brackets 11—12, and does not rest on block W^1 , said block serving only to prevent vertical play of W and serve as a support thereof in case the crate is reversed.

10 The blocks Y^1 and Z^1 serve in the same manner as the respective blocks W^1 and X^1 .

It may also here be noted that as the tongues 17 of the brackets 15—16 span the upper ends of the channels 8 and 10, the radiator X can not be let straight down into place but will have to be slightly angled and dipped into place, as indicated in Fig. 2.

It is understood that various modifications may be made in the general design and structural details of our invention, as herein disclosed, provided, however, that such modifications come within the spirit and scope of the appended claims.

Having now therefore fully shown and described our invention what we claim to be new and desire to protect by Letters Patent is:

1. A crate for radiators and the like having laterally projecting flange members, comprising side sections having channels to receive said flange members, opposed bracket members, arranged in staggered relation on each side section, to engage certain of said flanges to support the corresponding radiator ends above the radiator ends directly therebelow.

2. A crate for radiators and the like having laterally projecting flange members, comprising side sections having channels to receive said flange members, opposed bracket members, arranged in staggered relation on each side section, to engage certain of said flanges to support the corresponding radiator ends above the radiator ends directly therebelow, the ends of the bracket supported radiators opposite from said flanges being supported by the adjacent ends of the radiators therebelow.

3. A crate for radiators and the like having laterally projecting flange members, comprising side sections having channels to receive said flange members, opposed bracket members, arranged in staggered relation on each side section, to engage certain of said

flanges to support the corresponding radiator ends above the radiator ends directly therebelow and spacing blocks arranged between opposite ends of pairs of said radiators.

4. A crate for radiators and the like having laterally projecting flange members, comprising side sections having channels to receive said flange members, opposed bracket members, arranged in staggered relation on each side section, to engage certain of said flanges to support the corresponding radiator ends above the radiator ends directly therebelow and spacing blocks arranged between opposite ends of pairs of said radiators, said blocks having means for detachably securing the same on the respective radiators.

5. A crate for radiators and the like having laterally projecting flange members, comprising side sections having channels to receive said flange members, opposed bracket members, arranged in staggered relation on each side section, to engage certain of said flanges to support the corresponding radiator ends above the radiator ends directly therebelow and spacing blocks arranged between opposite ends of pairs of said radiators and spring members for yieldingly securing the blocks on the respective radiators.

6. A crate for radiators and the like having laterally projecting flange members, comprising side sections and a base, means for rigidly bracing a radiator upon the base, and brackets arranged in staggered relation on the side sections for engaging said flange members and bracing other radiators when the same are arranged over the first mentioned radiator and in alternating positions with respect thereto.

7. A crate for radiators and the like having laterally projecting flange members, comprising side sections, brackets secured upon the inner sides of said side sections, said brackets having pocket portions extending into the side sections for receiving and bracing the flanges, and transverse portions for supporting the flanges.

In testimony whereof we affix our signatures.

CORNELL FLAGSTAD.
OSCAR A. FLAGSTAD,
